[57] CLAIM

The ornamental design for a glass brick, as shown and
described.

DESCRIPTION

FIG. 1: is a front perspective view of a glass brick,
showing my new design;
FIG. 2: is a front view thereof;
FIG. 3: is a side view thereof;
FIG. 4: is a front perspective view as in FIG. 1 but
partially in transverse cross-section;
FIG. 5 is an enlarged view of a portion of the inner
surface visible in FIG. 4; and
FIG. 6 is a sectional view taken on line VI—VI of FIG.
5.

The other sides and the back are substantially like the
respective side and front shown.

FIG. 1

FIG. 2

FIG. 3

FIG. 4
